FIRING MECHANISM FOR MACHINE GUNS

Frederick T. Moore, East Hartford, Conn., assignor to Colt's Patent Fire Arms Manufacturing Co., Hartford, Conn., a corporation of Connecticut

Application July 29, 1932, Serial No. 625,684

3 Claims. (Cl. 89—27)

The invention relates particularly to a machine gun firing mechanism adapted for remote control. In accordance with the invention the machine gun may, for instance, be mounted upon the wing of an airplane, but may nevertheless be conveniently operated and fired by the pilot or the observer in his normal position. The object of the invention is to provide a firing control mechanism for the general purpose described which conveniently permits the firing of either single shots or volleys, and which is simple in construction and reliable in operation.

In the accompanying drawing I have shown two different embodiments of the invention and it will be understood that the drawing is intended to be for illustrative purposes only and is not to be construed as defining or limiting the scope of the invention, the claims forming a part of this specification being relied upon for that purpose.

20 Of the drawing:

Fig. 1 is a plan view of a machine gun and a firing mechanism therefor embodying the invention.

Fig. 2 is a side view of the machine gun shown in Fig. 1.

Fig. 3 is an enlarged fragmentary sectional view taken along the lines 3—3 of Figs. 1 and 11.

Fig. 4 is a fragmentary longitudinal sectional view taken along the line 4—4 of Fig. 3.

30 Fig. 5 is a fragmentary horizontal sectional view taken along the line 5—5 of Fig. 4.

Figs. 6, 7 and 8 are top, rear and side views respectively of the sear.

Figs. 9 and 10 are rear and side views respectively of the sear operating member.

Fig. 11 is an enlarged horizontal sectional view of the firing mechanism to which the invention particularly relates, this view being taken along the line 11—11 of Fig. 3.

40 Fig. 12 is a view similar to Fig. 11, but showing an alternative embodiment of the invention.

A firing mechanism embodying my invention is particularly adapted for use with a gun having a transversely and horizontally movable sear which is so constructed and positioned that it is adapted to be directly engaged through an opening in the side wall of the gun casing. Such a machine gun is shown in Patent No. 1,803,394 issued May 5, 1931 in the name of Christian Pfeiffer.

50 A somewhat similar machine gun is shown in Patent No. 1,803,350 issued May 5, 1931 in the name of George H. Tansley. In order that the present invention may be more clearly understood I have shown in the drawing and will now describe a gun such as that disclosed in detail in the aforesaid

Tansley patent. Reference may be had to the said patent for details of construction not herein fully presented.

The machine gun comprises a breech casing 1 which is generally rectangular in cross section and which is connected at the front with a trunnion block 2. The casing is closed at the rear by means of a plate 3 which carries a buffer mechanism indicated as an entirety by 4. Projecting from the casing at the front thereof is a barrel 5 which upon recoil is movable rearward to a limited extent. The barrel extends through a bearing aperture in the trunnion block 2 and has another bearing at or near the forward end of the barrel jacket 6, the said jacket being carried by a flange 7 formed on the trunnion block 2.

Positioned within the casing 1 is a breech bolt 8 which is held in locked relationship with the barrel at the instant of firing, but which during recoil moves rearward separately from the barrel 60 so that it, together with its associated parts, may effect ejection of the empty cartridge shell, cocking of the firing pin and loading of a new cartridge. All of these features of construction and operation are fully disclosed in the aforementioned 65 patents and detailed description thereof is not here necessary.

The breech bolt 8 has a central longitudinal opening therein adapted to receive a firing pin 9. A spring which is not shown serves to bias the 75 firing pin 9 for movement in the forward direction. Pivotedly mounted on the breech bolt is a cocking lever 10, the upper end of which extends into a suitable notch in the upper portion of the casing and the lower end of which extends 80 into a slot 9a in the firing pin. The cocking lever 10 is so formed and so related to the aforesaid notch in the upper portion of the casing that when the breech bolt moves rearward during recoil the cocking lever is turned in the clockwise 85 direction and serves to move the firing pin 9 relatively rearward to its cocked position where it is engaged by the sear to be now described.

The breech bolt 8 is provided at the rear with a transverse horizontal slot or guideway in which 100 is located a transversely and horizontally movable sear element 11. As illustrated the sear element 11 is the sear itself, but as to this the invention is not necessarily limited. As shown the sear element or sear 11 has a forward extending hook portion 11a which is adapted to engage a locking shoulder 9b formed on the firing pin 9 near the rear thereof. Preferably the shoulder 9b is the rear wall of a notch cut into the pin.

Carried by the breech bolt 8 immediately ad-

adjacent the sear 11 is a member 12 guided for rectilinear movement in a vertical slot in the breech bolt. Projecting from the top of the member 12 is a spring plunger 13 which normally abuts against the rear end of a member 14 carried by the breech bolt. The member 12 has a lug 12^a which abuts against the top of the sear and limits downward movement of the said member. The lug 12^a preferably has a V-point which enters a similarly shaped notch 9^b in the sear. The member 12 with the lug 12^a thereon thus serves as a detent to releasably hold the sear in its operative position. The sear is additionally held by means of a spring plunger 15 carried by a boss at the rear of the sear as shown most clearly in Figs. 5 and 6. The spring plunger 15 abuts against the said vertically movable member 12 as shown and thus also tends to hold the sear in its operative engagement with the firing pin.

Referring particularly to Fig. 5 it will be apparent that the firing pin 9 may be released to effect the firing of the gun by engaging the sear 11 at the left hand end thereof and moving it toward the right. In order that such engagement may be conveniently effected the side wall of the casing is provided with an opening 16 in register with the end of the sear.

Preferably the firing pin, the sear and the parts associated therewith are so constructed that the sear may be bodily reversed so that it may move from right to left instead of from left to right as shown and described. The feed mechanism may also be reversed so that the cartridge belt may be moved from right to left instead of from left to right. The details permitting such reversals and adjustments of parts are fully described in the aforesaid Tansley patent and repetition of the description is unnecessary.

During normal operation of the gun the rearward movement of the breech bolt is effected by the recoil action but in feeding the first cartridge preparatory to normal action it is necessary to manually move the bolt rearward. In order that the breech bolt may be so moved it is provided with a stud 17 which projects laterally through a slot 18 in the side wall of the casing. For engaging the stud 17 to operate the bolt 8 there is provided a charging slide, which may be of any usual or preferred construction. As shown there are brackets 19, 19^a on the side of the casing carrying a sleeve 20 slotted at the top and having therein a longitudinally movable rod 21. The rod 21 has thereon a hook member 21^a which engages the before-mentioned stud 17 and the rod 21 carries at the rear thereof a handle 22 by means of which it may be manually moved. It will be apparent that by moving the handle 22 rearward the breech bolt 8 can be moved rearward to effect the loading and cocking of the gun. If the gun is so located that the gunner cannot conveniently reach the handle 22 movement may be effected by means of a cord 23 connected to the hook member 21^a and adapted to extend to any convenient position.

One form of the remote control firing mechanism to which the invention particularly relates is shown in detail in Figs. 3 and 11. A bracket member 24 is provided which is rigidly secured to the gun casing, preferably at the side thereof opposite to that carrying the before-described charging slide. Preferably the side wall of the casing has therein not only the before-mentioned opening 16 but also a second opening 25. The front wall of the opening 16 and the rear wall of the opening 25 are preferably beveled as

shown. The bracket member 24 has thereon a lug 24^a with a beveled surface adapted to engage the beveled surface at the rear of the opening 25. Near the front of the bracket member 24 is an opening through which extends a bolt 26 having a beveled surface thereon adapted to engage the beveled surface at the front of the opening 16. It will be apparent that when the nut 26^a on the bolt 26 is tightened the bracket member 24 is forced against the side wall of the casing and is firmly held in place.

The bracket member 24 is provided with a central recess 27 in which is mounted a lever 28, this lever being pivoted on a vertical pin 29. A spring plunger 30 tends to move the lever 28 in the counter-clockwise direction, that is, from the operative position shown by full lines to the inoperative position shown by dotted lines. It will be observed that the spring plunger 30 is interposed between the bracket 24 and the longitudinally extending portion of the lever 28, being at the outer side of the said portion. Also mounted in the recess 27 in the bracket member 24 is a bell crank lever 31 pivoted for movement about a vertical pin 32. The forward extending arm of the lever 31 engages the inner surface of the rearward extending arm of the lever 28. The outward extending arm of the lever 31 projects through an opening in the outer wall of the bracket member 24. A spring plunger 33 tends to move the lever 31 in the clockwise direction, that is, from the operative position shown by full lines to the inoperative position shown by dotted lines. Connected with the outward projecting arm of the lever 31 is a flexible operating means which may be a tension member or cord 34. It will be obvious that the cord 34 may extend, preferably longitudinally, to any convenient position from which the gun is to be controlled and fired.

The lever 28 is so shaped and positioned that when the breech bolt 8 and the sear 11 are in their normal forward positions, as shown in Fig. 11, the said lever 28 is in register with the sear and is adapted to engage it upon being moved. It will be understood that when there is no tension on the cord 34 the levers 28 and 31 will be held by their respective spring plungers in the dotted line inoperative positions and the sear 11 will be in its normal position to hold the firing pin as shown in Fig. 5. However, when the cord 34 is tensioned the levers 31 and 28 are moved to the positions shown by full lines in Fig. 11, thus causing the sear 11 to be moved toward the right and thus effecting the release of the firing pin and the firing of the gun.

If only a single shot is desired the operator immediately releases the tension on the cord 34 and the two levers are then restored to their dotted line positions, thus permitting the sear, after recoil and cocking, to remain engaged with the firing pin. If, however, volley firing is desired tension is maintained on the cord 34 and the levers are held in the positions shown by full lines. The lever 28 is provided with a beveled surface at 28^a and as the breech bolt and sear move forward after recoil the said beveled surface 28^a serves to cam the sear inward and toward the right, thus immediately effecting firing. It will be obvious that in this way continuous firing may be effected.

In Fig. 12 I have shown a construction differing in detail from that shown in Figs. 3 and 11, but nevertheless embodying the invention. In lieu of the bracket member 24 there is provided

a bracket member 35 which is similarly held in place. A pivoted lever 36 is provided mounted for movement about a vertical pivot pin 37. The forward extending arm of this lever is similar in 5 function to the forward extending arm of the lever 28 and bears a similar relationship to the sear 11. The lever 36 has a rearward extending arm which is engaged by a spring plunger at 38 which normally tends to move the lever in the 10 counter-clockwise direction, that is, from the position shown by full lines to the position shown by dotted lines. The lever 36 also has an outward extending arm, the rear face of which is engaged by a plunger 39. A spring 40 surrounding 15 the plunger 39 normally tends to move it to its rear or retracted position. For moving the plunger 39 to its forward projecting position shown in the drawing there is provided a flexible operating member of the pressure type, as for 20 instance a Bowden wire. This member has an outer flexible casing 41 and an inner flexible wire which is movable longitudinally through the casing and which is connected with the plunger 39. The Bowden wire member can extend to any desired 25 position from which the gun is to be controlled and fired, and by applying pressure to the wire 42 the plunger 39 can be moved forward, thus moving the lever 36 to the position shown by full lines. This movement of the lever effects 30 firing of the gun in the way already fully described in connection with Fig. 11. If volley firing is desired the lever is maintained in the full line position.

I have already pointed out that the sear 11 is 35 preferably reversible and that the feeding mechanism may be capable of reversal or adjustment so that feeding can be effected in either direction. When the gun is so constructed I preferably provide for the attachment of the remote 40 control firing mechanism at either side thereof as desired. To this end there are provided in the right side of the casing holes 16^a and 25^a similar respectively to the before-mentioned holes 16 and 25. These permit the firing mechanism 45 as constructed as shown in Fig. 11 or as constructed as shown in Fig. 12, to be reversed in position and attached at the opposite side. In this connection it will, of course, be understood that when the firing mechanism is 50 attached at the right side the charging slide will be attached at the left side.

What I claim is:

1. A remote control firing mechanism for a machine gun having a casing with a breech bolt 55 therein movable rearward upon recoil and having on the breech bolt a longitudinally movable firing pin and a transversely and horizontally movable sear element, the said firing mechanism

comprising in combination, a bracket adapted to be attached to the casing at one side thereof, a lever vertically pivoted to the bracket and having an extension at one end and adapted to move transversely through an opening in the casing to directly engage and operate the horizontally movable sear element, a second lever vertically pivoted to the bracket and adapted to move the first said lever, and a flexible power transmitting tension member operably connected with the second lever and adapted to extend to the gun from a remote position of control. 80

2. A remote control firing mechanism for a machine gun having a casing with a breech bolt therein movable rearward upon recoil and having on the breech bolt a longitudinally movable firing pin and a transversely and horizontally movable sear element, the said firing mechanism comprising in combination, a bracket adapted to be attached to the casing at one side thereof, a lever vertically pivoted to the bracket and having an extension at one end and adapted to move transversely through an opening in the casing to directly engage and operate the horizontally movable sear element, the said lever extension having thereon a beveled surface which serves when the lever is maintained in its firing position to engage and operate the sear element as the breech bolt moves forward after recoil, a second lever vertically pivoted to the bracket and adapted to move the first said lever, and a flexible power transmitting tension member operably connected with the second lever and adapted to extend to the gun from a remote position of control. 90

3. A remote control firing mechanism for a machine gun having a casing with a breech bolt therein movable rearward upon recoil and having on the breech bolt a longitudinally movable firing pin and a transversely and horizontally movable sear element, the said firing mechanism comprising in combination, a bracket adapted to be attached to the casing at one side thereof, a lever vertically pivoted to the bracket and having an extension at one end and adapted to move transversely through an opening in the casing to directly engage and operate the horizontally movable sear element, a second lever vertically pivoted to the bracket and directly 115 engaging the first said lever to move it, two separate springs associated with the respective levers for biasing them toward their inoperative positions, and a flexible power transmitting tension member operably connected with the second lever and adapted to extend to the gun from a remote 120 position of control. 125
